(57) **CLAIM**

I claim the ornamental design for a wireless keyboard, as shown and described.

DESCRIPTION

FIG. 1 is a front perspective view of a wireless keyboard showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is a bottom perspective view thereof; and,

FIG. 10 is an enlarged view of the encircled portion in FIG. 1; and,

FIG. 11 is an enlarged view of the encircled portion in FIG. 6. The evenly spaced broken lines immediately adjacent the solid lines in the figures represent the bounds of the claimed design while all other evenly spaced broken lines are directed to environment and are for illustrative purposes only; the evenly spaced broken lines form no part of the claimed design.

The dot-dot-dash broken lines encircling portions of the claimed design that are illustrated in enlargements form no part of the claimed design.
